US00D951222S

(12) **United States Design Patent** (10) Patent No.: **US D951,222 S**
Su et al. (45) Date of Patent: **** May 10, 2022**

(54) **CONFERENCE DEVICE**

(71) Applicant: **Logitech Europe S.A.**, Lausanne (CH)

(72) Inventors: **Chun-Wei Su**, Hsinchu (TW); **Yuzheng Lu**, Shanghai (CN); **Shelly Chen**, Shanghai (CN); **Richard Hu**, Shanghai (CN); **Ku Chieh**, Shanghai (CN)

(73) Assignee: **Logitech Europe S.A.**, Lausanne (CH)

(**) Term: **15 Years**

(21) Appl. No.: **29/733,094**

(22) Filed: **Apr. 29, 2020**

(51) LOC (13) Cl. **14-03**

(52) U.S. Cl.

USPC **D14/140.11**; D14/130

(57) **CLAIM**

The ornamental design for a conferencing device, as shown and described.

DESCRIPTION

FIG. 1 is a top, front side perspective view of a conferencing device showing our new design;

FIG. 2 is a top, back side perspective view thereof;

FIG. 3 is a bottom perspective view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is a left side elevation view thereof; and,

FIG. 9 is a right side elevation view thereof.

The broken lines immediately adjacent to the shaded/contoured areas illustrate the bounds of the claim and form no part of the claimed design.

1 Claim, 5 Drawing Sheets
